TIMER

Thomas H. Corbett, Chicago, Ill.

Application September 15, 1952, Serial No. 309,609

10 Claims. (Cl. 161—7)

This invention relates to timing control means, and particularly to an automatically timed rinsing means for machines such as commercial dish or glass washers.

In commercial restaurant operation it is quite common to use glass washing apparatus wherein rotating scrubbing drums operating in a cleansing solution are utilized to scrub the inside and outside of each glass, and after such cleansing operation, the glasses are placed in wire racks or baskets and are transferred into a rinsing compartment of the machine where a rinsing operation with hot water is performed. One form of scrubbing drum utilized in such machines is disclosed in Vincent W. Cunningham Patent No. 2,153,238, patented April 4, 1939, but it will be recognized insofar as the present invention is concerned, other forms of scrubbing or washing apparatus may be utilized.

The above mentioned rinsing operation is considered to be important not only in removing the cleansing solution from the glass but also from the standpoint of the sterilizing effect that may be obtained by maintaining the rinsing water at a predetermined high temperature and continuing the rinsing operation for a pre-determined minimum period. This sterilizing action has been considered so important in recent years that under many of the public health codes in force in various cities and States, a minimum water temperature and a minimum rinse period have been established.

In an effort to simplify the matter of compliance with such public health codes, manufacturers of glass and dish washing equipment have embodied automatically controlled means for governing the rinse period, and it is with this aspect of the glass washing machine that the present invention is concerned. In the prior efforts to automatically control the rinse period, various expedients have been employed, but such expedients have almost universally been considered to be too costly, or have been difficult to repair and maintain. In view of this, it is the primary object of the present invention to simplify the attainment of an automatically controlled or timed rinse period in glass washing machines of the aforesaid type, and objects related to foregoing are to attain a timed rinse in such a machine through the use of mechanism that is simple and inexpensive in character and which may be repaired or replaced in a simple manner.

A further and important object of the present invention is to afford such a timed rinse structure for glass washing machines wherein the timing action is obtained by hydraulic means, and a further object is to attain this end through the use of a hydraulic unit that may readily be replaced without moving the glass washer and without disassembly of any of the major elements of the glass washer.

In the prior mechanisms for attaining a timed rinse in glass washers, it has been customary to employ electrical means which required the services of electrical workers not only in the assembly but in any repair or replacement, and these prior devices were somewhat difficult of installation because of the necessity for establishing electrical connections to the electrically operated elements, and in such prior devices the various electrical and electrically operated elements were disposed about and within the cabinet in such a way to make assembly and repair relatively difficult. In view of this it is a further object of the present invention to afford an automatic rinse controlling and timing mechanism that is constructed as a unit which may readily be in-

2

stalled on a glass washer cabinet and which may be readily connected with the related parts or elements of the apparatus, and objects related to the foregoing are to afford such a unit wherein a control valve, a strainer and a vacuum breaker required in such glass washing machines may be associated as a unit at a single location on the glass washer cabinet, thereby to facilitate assembly, and to provide a manifold which, when mounted in place on the cabinet, will readily permit the installation, removal or replacement of the strainer, the vacuum breaker and a hydraulic timing unit embodying the features of the invention.

Other and further objects of the present invention will be apparent from the following description and claims and are illustrated in the accompanying drawings which, by way of illustration, show a preferred embodiment of the present invention and the principle thereof and what I now consider to be the best mode in which I have contemplated applying these principles. Other embodiments of the invention embodying the same or equivalent principles may be used and structural changes may be made as desired by those skilled in the art without departing from the present invention and the purview of the appended claims.

25 In the drawings:

Fig. 1 has top front perspective view of a glass washer embodying the timed rinse mechanism of the present invention;

Fig. 2 is a fragmental vertical sectional view taken 30 substantially along the line 2—2 of Fig. 1;

Fig. 3 is an enlarged fragmentary elevational view of the timing unit and the related strainer and vacuum breaker elements, the view being taken at an enlarged scale from the line 3—3 of Fig. 2;

35 Figs. 4, 5 and 6 are schematic vertical sectional views taken through the timing and the valve mechanism and showing this apparatus in different positions which are assumed in the cycle of operation of the timer; and

Fig. 7 is a fragmentary plan sectional view taken substantially along the line 7—7 of Fig. 6.

40 For purposes of disclosure the invention is herein illustrated as embodied in glass washer 20 having a floor mounted cabinet C within the upper side of which a multiple compartment sink structure is mounted which affords a washing compartment 21, a flushing compartment 22 and a rinsing compartment 23. The washing compartment 21 is located along the forward side of the cabinet and extends substantially one-half way to the rear side of the cabinet, the flushing compartment occupying the remainder of the space between the washing compartment and the rear wall of the structure. The rinsing compartment 23 occupies the right hand end portion of the sink structure and extends entirely between the front and rear walls of the sink structure. 45 It will be noted that the division wall between the rinsing compartment and the other two compartments is located substantially midway between the end walls of the cabinet, and this enables a sliding cover 24 to be positioned selectively over the rinsing compartment 23, or over the other two compartments. This conventional cover structure and relationship is utilized in facilitating the handling of the glasses and the trays or baskets in which such glasses are placed for convenience of handling after washing.

50 The washing compartment 21 has a pair of glass washing drums 25 mounted therein on vertical axes in substantially the manner disclosed in the aforesaid Cunningham patent, and these glass washing drums 25 are arranged to operate in a submerged condition, the cleansing solution being provided in the compartment 21 so as to be above the upper level of these drums. The flushing compartment 22 has a removable perforated pan 22P mounted therein, and a pair of flushing nozzles 22F are extended through the bottom of this pan so that glasses that are unusually dirty may be flushed before being washed in the constantly rotating scrubbing drums 25. During the washing operation, the cover 24 is located, in its right hand position over the rinsing compartment 23, so that a rinsing operation may be in progress during such washing of further glasses, and a basket is normally located at

top of the cover 24 so that the glasses may be placed in such basket according to conventional practice after the washing has been completed. The cover 24 is then slid to the left so as to disclose the interior of the rinsing compartment 23, and any glasses contained therein are removed. The loaded tray of the newly washed glasses is then loaded into the rinsing compartment on to a pair of supporting rods 26 that are spaced upwardly from the bottom wall of the rinsing compartment. The newly washed basket of glasses is then in position for the performance of the rinsing operation, and after closure of the cover 24, this is accomplished by a conventional rotating rinsing arm 27 located in the bottom of the rinsing compartment 23 below the level of the rods 26 and by an upper stationary 15 spray 28 that projects through the back wall of the rinsing compartment adjacent to the upper edge thereof.

The rinsing operation is initiated and automatically timed and controlled by a timing unit 30, embodying the features of the present invention, and located on an upwardly facing rear ledge 31 that is formed along the rear edge of the sink structure, the unit 30 in the present instance being located directly behind the rinsing compartment 23 so as to simplify the assembly of the structure.

As shown in Fig. 2 of the drawings, the shelf 31 is provided as a horizontal strip connecting the rear wall 23R of the rinsing compartment 23 and the rearwardly spaced rear wall 32 of the cabinet C, and the control unit 30 under the present invention is so constructed and arranged that a common mounting casting 35 permanently fixed to the lower face of the shelf 31 in the space between the walls 23R and 32 serves as a mounting for accessibly supporting and operatively associating those elements of the control unit 30 to which access must be had from time to time. Such elements comprise a removable strainer 38, a replaceable valve unit 39, a hydraulic timer and control mechanism 40, a vacuum breaker 41 and the nozzle 28. The casting 35 is elongated in form and has horizontal flanges 35F and a web portion 35W forming a generally flat upper surface 35S that fits against the lower face of the ledge 31 and is secured thereby by a plurality of screws 42 extended through the ledge 31 and threaded into the casting 35, and at spaced points along such upper surface 35S upwardly extending mounting or connecting means project through appropriate openings in the shelf or ledge 31 for connection or mounting of the strainer 38, the valve unit 39 and the vacuum break 41, as will be described hereinafter.

Thus, at the left end of the casting 35S, as shown in Fig. 3, an upwardly extended sleeve 45 is formed which affords an upward continuation of a vertical chamber 46 that is formed in the casting 35. This chamber 46 terminates at its lower end in an upwardly facing annular shoulder 46S, and beyond this shoulder an inlet passage 47 extends downwardly through a connecting nipple 48 which projects from the bottom of the casting 35. At its upper end the sleeve 45 is internally threaded so that the cap 38C of the strainer unit 38 may be removably mounted as a closure for the upper end of the chamber 46. The strainer comprises a cylindrical screen 38A, the lower end of which is seated on the shoulder 46S. At its upper end the screen 38A is seated in a generally spherical recess 38B formed in the strainer cap 38C. Water entering the inlet 47 and passing through the strainer 38 passes to the right from the chamber 46 through a horizontal passage 49 into a lower valve chamber 50 which is located beneath an upper valve chamber 51, and these two chambers are divided by an annular locating ledge or shoulder 52. At its upper end the chamber 51 is defined by an upwardly projecting nipple 53 which serves as a mounting means for the valve unit 39, and this valve unit extends downwardly into the chambers 51 and 50 and cooperates with the shoulder 52 so as to control flow of water from the lower chamber 50 to the upper chamber 51 as will be described in detail hereinafter.

Water that passes the valve into the upper chamber 51 then flows to the right, Fig. 3, through a horizontal passage 54 and then upwardly through an upwardly projecting externally threaded nipple 55. This nipple 55 constitutes one element of the mounting for the vacuum breaker 41, and the other mounting element is afforded by a similar nipple 56 located near

the right hand end of the casting 35 as shown in Fig. 3. The nipple 56 opens downwardly into a distributing or outlet chamber 57, formed in the casting 35, the lower end of such chamber 57 terminating in a downwardly projecting nipple 58 through which connection with the rotating spray structure 27 may be established in the usual manner. The outlet chamber 57 also has a forward extension 59 into which the nozzle 28 is threaded so that the nozzle 28 also receives water from the chamber 57. The nozzle 28 has a flange 28F which clamps the wall 23R against the annular end of the member 59. As shown in Fig. 2, the casting 35 has a rearward projection 59R similar to the element 59, this element 59R being cast solid and affording means whereby the casting may be readily used for either right or left hand mounting.

The vacuum breaker 41 is of conventional form and has its inlet connected by a fitting 62 to the upper end of an inlet pipe 63, the lower end of which is connected by a fitting 64 to the nipple 55. The outlet of the vacuum breaker 41 is connected by an elbow 65 and a fitting 66 to the upper end of a pipe 67, the lower end of which is connected by a fitting 68 to the nipple 56.

The valve assembly 39 is conventional in structure and includes a mounting cap 70 with a downwardly extended internally screw threaded annular flange 70F and an upwardly extended concentric externally threaded nipple 70N. The nipple 70N has an internal or axial bore 70B therein which terminates in a lower annular shoulder 70S, Fig. 5, and a valve stem 71 is slidably extended through the bore 70B. The stem 71 has an upper head 71H which overlies the bore 70B, and an expansive coil spring 72 surrounds the stem within the bore and acts against the lower face of the head 71H. The lower end of the spring 72 acts on a packing washer 73 to press packing material 74 against the shoulder or flange 70S.

The valve stem 71 extends downwardly through a hollow sleeve 75 which abuts at its upper end against the lower surface of the cap 70, within and in inwardly spaced relation to the internally threaded flange 70F. Near its lower end the sleeve 75 has an inwardly directed annular guiding flange 75F which guides the stem 71, and below this flange 75F the stem has an upwardly extended axial bore 76 from which a plurality of radial bores or valve passages 77 extend. Against the lower end of the sleeve 75 a stationary metal valve seat 78 is positioned, this seat having a circular central opening 78P that is of larger diameter than the stem 71 so as to afford an annular valve passage about the stem. This annular valve passage constitutes the valve post and is controlled by a valve washer 80 fixed on the lower end of the valve stem 71 by means including a retainer 81 and a nut 82 threaded onto the lower end of the valve stem 71. The valve 39 is mounted by inserting the valve downwardly into the chamber 51 and tightening the threaded flange 70F onto the nipple 53, and this firmly presses the seat 78 onto the flange or seat 52 of the casting 35. Thus the valve member 80, which is urged normally to its seated or closed relation by the spring 72, serves to govern flow from the chamber 50 to the chamber 51, and the valve may be opened by downward actuation of the valve stem 71.

The hydraulic timing and control unit 40 is best shown in Figs. 3 and 4 of the drawings and is afforded by a sectional cylindrical casing having a lower section 85, an upper section 86, a cover 87 and an operating handle 88 that has rounded actuating head 88H and a downwardly projecting stem 88S that extends slidably downwardly through the cover 87.

The lower section 85 of the casting is cylindrical in form with a relatively heavy lower wall 85L and a relatively thin upwardly extending side wall 85W. The lower wall 85L has a downwardly extending mounting sleeve 89 formed thereon which is concentric with the wall 85W and which is internally threaded so that the section 85 may be mounted on the nipple 70N in axial alignment with the valve 39 and with the head 71H of the valve stem located within a clearance chamber 89C that is afforded within the sleeve 89. This clearance chamber provides for the required up and down movement of the head 71H.

The lower section 85 also has an upstanding central

guide sleeve 85S formed therein and affording an axial guide passage 85P that extends downwardly through the wall 85L and opens into the chamber 85C, and this guide passage serves to receive and guide a valve actuating stem 90 that is slidably disposed within the passage 85P. The guide sleeve 85S extends upwardly to a level somewhat above the upper edge of the outer wall 85W, and the upper end of the valve actuating stem 90 is arranged to project upwardly beyond the upper end of the sleeve 85S for a distance sufficient to permit downward valve-actuating movement of the stem 90, and in such valve actuating movement the stem 90 is moved from a position of Fig. 4 to the position of Fig. 5.

The valve actuating stem 90 may be locked in its lower or valve-opening position by locking means that are arranged in the present embodiment to act between the guide sleeve 85S and the stem 90. In the form herein shown, such latching or locking means are afforded by a plurality of locking balls 92 that are disposed in a plurality of apertures 93 that are extended radially through the sleeve 85S near the upper end thereof. These balls 92 are arranged to move inwardly within the apertures 93 from the released position shown in Fig. 4 to the locking position shown in Fig. 5 when the valve actuating stem 90 is actuated to its lower or valve-opening position, and when the locking balls 92 thus move to their inward positions, they engage an annular locking groove 94 that is formed in the stem 90. When the locking balls 92 thus assume their locking positions, they are latched in this relationship by a latching sleeve 95 which slidably surrounds the upper end of the sleeve 85S as shown in Figs. 4 and 5. The latching sleeve 95 is of course urged yielding downwardly by gravity and tends in its downward movement to force the balls 92 to their inner or locking positions. Thus, it will be noted that the sleeve 95 at its lower end has a relatively large internal annular surface 95L and above this surface an inwardly sloping cam surface 95S is formed. Thus, when the latching sleeve 95 is in its upper position, the surface 95L is opposite the location and locking balls 92, thus to allow these locking balls to move outwardly to the released position shown in Fig. 4, and the locking balls in this position are ineffective. In causing the outward shifting movement of the locking balls 92, the concave character of the groove 94 acts to impart the desired outward forces due to the upward urging of the stem 90 by the valve spring 72. As a matter of convenience, the upward movement of the latching sleeve 95 is limited by a C-washer 96.

With the structure thus described, the valve 39 may be opened by downward actuation of the operating stem 90 and the locking balls 92 become automatically effective to lock the stem 90 in its valve-opening position. In order to release the locking balls 92 and permit closure of the valve 39, it is necessary to raise the latching sleeve 95 from its lower effective position shown in Fig. 5 to its upper released position shown in Fig. 4, and this is accomplished by hydraulic timing means included within the lower section 85 of the timing and control unit 40.

The outer wall 85W and the central sleeve 85S serve to afford a liquid chamber 85C within the section 85, and this chamber of course is annular in character. Within such chamber an annular float 100 is mounted in a slidable relation about the central sleeve 85S, and this float is buoyed up by a body of liquid 101 that is contained within the chamber 85C. In the present instance, the float 100 is made from metal and the requisite buoyance is afforded by using a heavy liquid. Preferably this heavy liquid is afforded by a body of mercury that has a small proportion of a lubricating liquid such as the liquid originally used in hydraulic brake systems. Lubricating liquid such as hydraulic brake fluid acts as an inhibitor to prevent or minimize corrosion or tarnishing of the mercury. In addition to the buoyant action of the liquid 101, additional resilient upward forces are applied to the float 100 by a relatively light coil spring 102 that surrounds the sleeve 85S and acts between the lower wall 85L and the bottom of the float 100. The spring 102 is utilized merely to induce faster return of the float to its floating position, and the spring therefore is of limited length

80

and strength so as to be effective only in initiating the return or upward movement of the float.

The float 100 may be formed cup-like in form in that an annular recess 100R is extended downwardly from the upper face of the float, thus to provide an outer wall 100W and an inner wall or sleeve 100S. The recess 100R thus affords a space within which liquid 101 may be placed so as to reduce or vary the buoyance of the float, and a timing action is attained by allowing any liquid within the recess or cup 100R to flow gradually out of the cup at a controlled rate through a discharge opening or orifice 102 that is formed through the wall 100W at the level of the lower wall of the recess 100R. The normal level of the liquid 101 in the chamber 85C is such that the cup may be filled by downward actuation of the cup or float 100 from its upper position of Fig. 4 to the lower position of Fig. 5, and this is accomplished by operation of the handle 88 which not only actuates the float to its lower position, but also operates the stem 90 to its lower or valve-opening position.

Thus, as shown best in Figs. 3 and 4 of the drawings, the upper housing section 86 is formed for mounting as a closure on the upper end of the lower housing section 85, and the upper housing section 86 has a relatively thick lower wall 86L that is externally screw threaded at 86X so that it may be threaded into the upper end of the section 85 to an extent limited by a flange 86F on the wall 86L. The upper section 86 is defined primarily by an upwardly extending and relatively thin wall 86W into which a reduced flange 87F of the top wall 87 is extended and screws 87S extended through wall 86W and into the flange 87F serve to hold these parts in their assembled relationship.

The lower wall 86L has a central passage 86B and this passage is extended downwardly about the upper end of the sleeve 85S by an annular downwardly projecting collar 86C, and as best shown in Fig. 4, the passage 86B serves as a guide for a vertically slidable operating sleeve 105. This operating sleeve 105 has a head 105H at its upper end and an expansive coil spring 106 acts upwardly against this head to urge the sleeve 105 toward its upper position shown in Figs. 3 and 4, and in such upward movement the head 105H engages a lower retaining flange 88F on the stem 88S so that the handle 88 is also urged to its upper position. At its lower end the spring 106 acts against a packing ring 107 which acts on packing 108 within an enlarged portion of the bore 86B to afford a liquid seal above the sleeve 105. Within the sleeve 105 and at the lower face of the head 105H, a hardened abutment pad 109 is mounted in a central position so that when the actuating sleeve 105 approaches the limit of its downward movement, the pad 109 engages the upper end of the stem 90 to actuate the same to its valve-opening position. The relationship is such that the lower end 105E of the sleeve 105 engages the bottom of the cup 100R and moves the cup downwardly for a substantial distance prior to the engagement of the pad 109 with the stem 90 so that the stem 90 is actuated only during the final downward portion of the movement of the operating handle 88.

As the float 100 is thus moved to its downward or lower position it is completely submerged within the body of liquid of 101, and the cup 100R is thus completely filled with liquid as shown in Fig. 5. Then, upon release of the handle 88, the float 100 rapidly shifts upwardly for a short distance and to such a level that the upper edge of the cup is above the level of the surrounding liquid 101. At this time of course the valve operating stem 90 remains in its lower or valve-opening position due to the action of the locking of balls 92. As soon as the float 100 returns to the position wherein the upper edge of the cup 100R is above the liquid level in the chamber 85C, flow of liquid commences from the cup 100R through the metering orifice 102 so that upward movement of the flow thereafter progresses at a controlled rate. This attains a timing action which has been found to be extremely accurate where it has been used to govern a rinse period a minimum length of 15 seconds. As the upward movement of the float progresses, the upper end of the sleeve 100S approaches the lower end of the latching sleeve 95, and in the final portion of the upward movement of the float, the latching sleeve 95 is moved to its released position of Fig. 4. This releases the balls 92 and stem 90 returns to its

upper position due to the valve-closing action of the spring 72.

It should be pointed out that the float 100 is made from metal, aluminum being used in the present instance, and the float is thus buoyed up with considerable force due to the extremely high specific gravity of the mercury that constitutes the major portion of the liquid in the chamber 85C. As pointed out hereinabove, the liquid does have a small amount of a lubricant included therein; but this added constituent, which is of course of low specific gravity, constitutes but a very minor proportion so that it does not materially change the specific gravity of the liquid material in the chamber 85C. The lubricant liquid also serves as a protecting covering over the body of mercury, and even when this lighter liquid attains a position of rest on top of the body of mercury, the level of the mercury is sufficiently high to buoy the float 100 to its upper position in which the latch means are released. The lubricating component of the liquid body of course may become mixed with the mercury to some degree in the course of operation of the timer, but, as hereinabove pointed out, this does not materially alter the effective buoyant action of the body of mercury.

As herein disclosed, the setting means are such that the float 100 is first moved in a downward direction, and the control stem 90 is thereafter shifted to its actuated position; but it should be pointed out that except for the resulting simplification in the actuating or setting means, this sequence of operation is immaterial.

From the foregoing description, it will be apparent that the present invention enables the construction of glass washers and the like to be materially simplified through the elimination of magnetic valves and electrical timing means such as have been considered essential in the past. Moreover, it will be evident that the present timer is one that is not only simple in its structure and reliable in its operation, but it is adapted to be located in a conveniently accessible location so that the servicing or replacement thereof may be readily accomplished. Such servicing and replacement may, of course, be done by an ordinary mechanic so as to make the upkeep and servicing of the glass washer relatively inexpensive.

Thus, while I have illustrated and described the preferred embodiment of my invention, it is to be understood that this is capable of variation and modification, and I therefore do not wish to be limited to the precise details set forth, but desire to avail myself of such changes and alterations as fall within the purview of the following claims.

I claim:

1. In an automatic timer adapted for controlling association with a spring-closed valve to hold such valve open for a predetermined period, a main body adapted to be mounted on such a valve and having a movable valve opening member mounted thereon for movement between a released position and a valve-opening position, latch means for holding said valve opening member in said valve opening position, said body having a chamber therein, an open top cup-like float mounted in said chamber and operatively related to said latch means to release said latch means when said float is in an upper releasing position, said chamber having liquid therein to a level effective normally to raise said float to such an upper position, setting means for pressing said valve opening member to its valve opening position and submerging said float to a lower position wherein the cup-like float is filled with said liquid, means yieldingly urging said float to an intermediate position wherein the level of such liquid in said float is higher than the level of such liquid in said chamber, said float having a drain opening therein of predetermined area through which liquid drains from said float at a predetermined rate whereby said float is buoyed upwardly from said intermediate position to said upper releasing position in a predetermined time interval.

2. In an automatic timer adapted for controlling association with a spring-closed valve to hold such valve open for a predetermined period, a main body adapted to be mounted on such a valve and having a movable valve opening member mounted thereon for movement between a released position and a valve-opening position, latch means for holding said valve opening member in said valve opening position, said body having a chamber therein, an open top cup-like float mounted in said chamber and operatively associated with said latch

means to release said latch means when said float is in an upper releasing position, said chamber having liquid therein to a level effective normally to raise said float to such an upper position, setting means for pressing said valve opening member to its valve opening position and submerging said float to a lower position wherein the cup-like float is filled with said liquid, said float having a drain opening therein of predetermined area through which liquid drains from said float at a predetermined rate whereby said float is buoyed upwardly to said upper releasing position at a predetermined rate.

3. In an automatic timer adapted for controlling association with a spring-braced valve to hold such valve in an actuated position for a predetermined period, a main body adapted to be mounted on such a valve and having a movable valve actuating member mounted thereon for movement between a released position and an actuated position, latch means for holding said valve actuating member in said valve actuating position, said body having a chamber therein, an open top cup-like float mounted in said chamber and operatively associated with said latch means to release said latch means when said float is in an upper releasing position, said chamber having liquid therein to a level effective normally to raise said float to such an upper position, setting means for pressing said valve opening member to its valve opening position and submerging said float to a lower position wherein the cup-like float is filled with said liquid, said float having a drain opening therein of predetermined area through which liquid drains from said float at a predetermined rate whereby said float is buoyed upwardly to said upper releasing position at a predetermined rate.

4. In an automatic timer adapted for controlling association with a spring-closed valve to hold such valve open for a predetermined period, a main body adapted to be mounted on such a valve and having a movable valve-opening member mounted thereon for movement between a released position and a valve opening position, latch means for holding said valve opening member in said valve opening position, said body having a chamber therein, a float having a relatively large upper inlet opening and mounted in said chamber and operatively associated with said latch means to release said latch means when said float is in an upper releasing position, said chamber having liquid therein to a level effective normally to raise said float to such an upper position, setting means for pressing said valve opening member to its valve opening position and shifting said float to a lower position wherein liquid enters said inlet opening to fill said float with said liquid, means yieldingly urging said float to an intermediate position wherein the level of such liquid in said float is higher than the level of such liquid in said chamber, said float having a drain opening therein of predetermined area through which liquid drains from said float at a predetermined rate whereby said float is buoyed upwardly from said intermediate position to said upper releasing position at a predetermined rate.

5. In an automatic timer adapted for controlling association with a spring-biased valve to hold such valve in an actuated position for a predetermined period, a main body adapted to be mounted on such a valve and having a movable valve-actuating member mounted thereon for movement between a released position and a valve-actuating position, latch means for holding said valve actuating member in said valve actuating position, said body having a chamber therein, a float having a relatively large upper inlet opening and mounted in said chamber and operatively associated with said latch means to release said latch means when said float is in an upper releasing position, said chamber having liquid therein to a level effective normally to raise said float to such an upper position, setting means for pressing said valve opening member to its valve actuating position and submerging said float to a lower position wherein liquid enters said inlet opening to fill said float with said liquid, said float having a drain opening therein of predetermined area through which liquid drains from said float at a predetermined rate whereby said float is buoyed upwardly to said upper releasing position at a predetermined rate.

6. In an automatic timer adapted for controlling association with a spring-biased device to hold such device in an actuated position for a predetermined period, a main body adapted to be associated with such a device and having a movable control member mounted thereon for

movement between a released position and an actuated position, latch means for holding said member in said actuated position, said body having a chamber therein, a float having a relatively large upper inlet opening and mounted in said chamber and operatively associated with said latch means to release said latch means when said float is in an upper releasing position, said chamber having liquid therein to a level effective normally to raise said float to such an upper position, setting means for pressing said control member to its actuated position and submerging said float to a lower position wherein liquid enters said inlet opening to fill said float with said liquid, a means yieldingly urging said float to an intermediate position wherein the level of such liquid in said float is higher than the level of such liquid in said chamber, said float having a drain opening therein of predetermined area through which liquid drains from said float at a predetermined rate whereby said float is buoyed upwardly from said intermediate position to said upper releasing position at a predetermined rate.

7. In an automatic timer adapted for controlling association with a spring-biased device to hold such device in an actuated position for a predetermined period, a main body adapted to be associated with such a device and having a movable control member mounted thereon for movement between a released position and an actuated position, latch means for holding said member in said actuated position, said body having a chamber thereing, a float having a relatively large upper inlet opening and mounted in said chamber and operatively associated with said latch means to release said latch means when said float is in an upper releasing position, said chamber having liquid therein to a level effective normally to raise said float to such an upper position, setting means for pressing said control member to its actuated position and submerging said float to a lower position wherein liquid enters said inlet opening to fill said float with said liquid, said float having a drain opening therein of predetermined area through which liquid drains from said float at a predetermined rate whereby said float is buoyed upwardly to said upper releasing position at a predetermined rate.

8. In a timer, a main body having a liquid compartment therein and also having a setting handle mounted thereon for movement from a normal retracted position through a setting stroke, means biasing said handle to said normal retracted position, an operating and control member mounted in said body for movement by said handle, in a setting stroke thereof, from a released position to an operated position, latch means operable to latch said control member in said operated position, and means for releasing said latch comprising a cup-shaped float mounted in said compartment, liquid in said chamber for buoying said float to a normal elevated position, means associated with said handle for moving said float downwardly to a lower set position in said chamber when said handle is operated through a setting stroke, said float having an open-top liquid chamber therein that fills with liquid when said float is moved to said lower set position, spring means effective when said handle returns to said normal position to raise said float to an intermediate position wherein the liquid level in said chamber is higher than the liquid level in said compartment, said float having a metering orifice from said chamber through which liquid may flow from said chamber to said

compartment, and means operated by said float when it reaches said normal elevated position to release said latch means.

9. In a timer, a main body having a liquid compartment therein and also having a setting handle mounted thereon for movement from a normal position through a setting stroke, means biasing said handle to said normal retracted position, an operating and control member mounted in said body for movement by said handle, in a setting stroke thereof, from a released position to an operated position, latch means operable to latch said control member in said operated position, and means for releasing said latch comprising a float having a chamber therein with a relatively large upper inlet opening and a lower metering orifice through which liquid may flow, said float being mounted in said compartment, liquid in said chamber for buoying said float to a normal elevated position, means associated with said handle for moving said float downwardly to a lower set position in said chamber when said handle is operated through a setting stroke so that said liquid chamber fills with liquid entering said inlet opening, spring means effective when said handle returns to said normal position to raise said float to an intermediate position wherein the liquid level in said compartment is higher than the liquid level in said compartment, and means operated by said float when it reaches said normal elevated position to release said latch means.
10. In a timer, a main body having a liquid compartment therein and also having a setting handle mounted thereon for movement from a normal position through a setting stroke, means biasing said handle to said normal retracted position, an operating and control member mounted in said body for movement by said handle, in a setting stroke thereof, from a released position to an operated position, latch means operable to latch said control member in said operated position, and means for releasing said latch comprising a float having a chamber therein with a relatively large upper inlet opening and a lower metering orifice through which liquid may flow, said float being mounted in said compartment, liquid in said chamber for buoying said float to a normal elevated position, means associated with said handle for moving said float downwardly to a lower set position in said chamber when said handle is operated through a setting stroke so that said liquid chamber fills with liquid entering said inlet opening, and means operated by said float when it reaches said normal elevated position to release said latch means.
